[57] CLAIM

The ornamental design for a combined motor housing and base unit for a fan, as shown and described.

DESCRIPTION

FIG. 1 is a left rear perspective view of the "combined motor housing and base unit for a fan";

FIG. 2 is a left front perspective view;

FIG. 3 is a left side elevational view;

FIG. 4 is a front elevational view;

FIG. 5 is a rear elevational view;

FIG. 6 is a right side elevational view;

FIG. 7 is a top view; and,

FIG. 8 is a bottom view.

The broken-line showing of environmental structure in FIGS. 1-6 is for illustrative purposes only and forms no part of the claimed design.
